C. C. HANSEN,
OIL BURNING FORGE,
APPLICATION FILED JUNE 13, 1921.

1,415,553.

Patented May 9, 1922.

Fig. 2.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

OIL-BURNING FORGE.

1,415,553.

Specification of Letters Patent.

Patented May 9, 1922.

Application filed June 13, 1921. Serial No. 477,221.

To all whom it may concern:

Be it known that I, CHARLES C. HANSEN, a citizen of the United States, a resident of Easton, Northampton County, and State 5 of Pennsylvania, have invented a certain Oil-Burning Forge, of which the following is a specification accompanied by drawings.

This invention relates to oil burning forges for heating drill steels or similar 10 articles, but more particularly to a modification of the type of forge described in United States Patent, No. 1,361,829, granted to me December 7, 1920.

The objects of the present invention are 15 to improve in some respects upon the forge described in said patent and enable the forge to be constructed with a renewable lining composed of blocks of refractory material, most of which are of standard construction instead of special blocks to form the combustion chamber, and to build the combustion chamber substantially with standard blocks so that the chamber will have a conformation adapted to divide the 20 flame vertically and cause the flame portions to travel in ascending spirals for heating the articles to be forged. By this means, as in forges of this type, the heat is evenly distributed throughout substantially 25 the whole chamber and time is afforded for substantially complete combustion 30 of the fuel, thus adding greatly to the efficiency of the forge.

Although the forge disclosed in this application is primarily designed for burning oil, the invention could be adapted for use with substantially any kind of fuel which can be projected through a nozzle whether liquid or solid, and it is to be understood that the drawings are illustrative only and show one preferred form of the forge.

In the drawings, Figure 1 is a transverse vertical sectional view taken through the forge on the line 1—1 of Figure 3, looking 45 in the direction of the arrows.

Figure 2, is a diagrammatic perspective view of the refractory lining blocks showing their relation to each other as they are assembled, the blocks at one end and at the 50 front being removed.

Figure 3, is a top plan view of the forge with the cover removed and the casing in horizontal section, and

Figure 4, is a detail perspective view of 55 the lower central back lining block.

Referring to the drawings, the forge may be mounted on a suitable column A and preferably comprises a metallic casing B having a fuel aperture C in the lower portion of the front wall D for the introduction 60 of combustible fuel under pressure through a suitable nozzle E. The oil or fuel enters the inlet pipe F controlled by the valve G and air under pressure enters the pipe H controlled by the valve J as usual in fuel 65 nozzles of this type.

The cover K' is formed with a horizontally extending elongated aperture K adapted to be located above the fuel aperture C in the front wall of the casing for the insertion of a plurality of drill steels L or other articles to be forged. The cover K' is provided with a similar aperture P at the back for the escape of products of combustion.

The front lining portion of the casing 75 comprises the refractory blocks Q through which a lower aperture R is formed registering with the aperture C for the nozzle E. The base may be formed of the blocks T and 80 U of refractory material laid as indicated in Figure 2.

The lower lining block a at the back, as shown, is a special wedge shaped block, the apex b of the wedge lying vertically and opposite the nozzle E. This lower central block a is preferably of double thickness from its base to its apex and substantially equal in height to the height of two back lining blocks e. The ends of the central 90 block a are preferably under-cut at c and d so that the narrower standard back lining blocks e of ordinary construction may be built into the said under-cut portion as shown particularly in Figure 2. These lining blocks e form the first and second tiers, and wider standard lining blocks f complete 95 the tiers at the back, while similar blocks, preferably of narrower width, form the sides of the lining. By means of this construction, pockets or recessed chambers are formed at the back wall of the combustion chamber at each side of the center, with over-hanging raised portions formed by the wider blocks f.

The cover K' is preferably lined with a plurality of blocks h placed transversely inside the top and at the ends of the cover, but leaving the sides of the cover open opposite the apertures K and P.

105

110

The drill steels L are inserted through the opening K, while the products of combustion escape through the opening P. Some of the products of combustion may escape at the 5 front of the forge through the opening K and a screen (not shown) is usually provided at the front to protect the workman from the heat and escaping products of combustion.

10 In the operation of the forge, the flame is directed against the back block a along the line of the arrows 6 in Figures 1 and 2. The remaining arrows indicate that the flame is split or divided at the central 15 wedged portion of the lower back block " and ascends in double spirals through the recessed portions at each side of the combustion chamber in order to heat the drill steels. The arrows are also indicated dia- 20 grammatically to some extent in Figure 3.

One advantage of this construction resides in the fact that the flame from one centrally located burner is distributed equally and evenly over a wide surface for 25 the purpose of evenly heating drill steels regardless of the place they occupy in the forge. Another advantage is the ability to heat a plurality of steels at one time, because of the relatively long opening provided at the front of the forge, which is 30 made possible by the lining block construction shown and described. Furthermore, with the exception of one special block a at the center, all the lining blocks are of stand- 35 ard rectangular construction of sizes pur- chasable upon the market, which cheapens the cost of the forge and permits ready as- sembling. I am enabled to construct a 40 forge with the requisite shape of the back lining provided with recessed or under-cut portions forming chambers, by using only 45 one special block.

I claim:

1. An oil burning forge, comprising a 45 casing having a renewable lining composed of blocks of refractory material, the lower central block being wedge shaped and projecting towards the fuel inlet of the forge in order to divide the flame vertically, the 50 remaining blocks being of standard rectangular construction and the conformation of the chamber being adapted to cause the portions of the divided flame to ascend at both sides of the central block in double spirals 55 for heating the articles to be forged, there- by distributing the heat substantially

throughout the whole chamber and retard- ing the flame to afford substantially com- 60 plete combustion.

2. An oil burning forge, comprising a 60 casing having a fuel aperture in the lower portion of its front wall for the distribution of combustible fuel under pressure, another horizontal elongated aperture above the fuel 65 aperture for the insertion of a plurality of articles to be forged, a waste gas aperture at the back of the structure for the escape of the products of combustion, and a renew- 70 able lining for the casing composed of blocks of refractory material, the lower cen- 75 tral block being wedge shaped and project- ing towards the fuel inlet of the forge in order to divide the flame vertically, the re- 80 maining blocks being of standard rectangu- lar construction and the conformation of the chamber being adapted to cause the portions of the divided flame to travel in double as- 85 cending spirals for heating the articles to be forged, whereby time is afforded for more complete combustion and the heat is distrib- 90 uted throughout substantially the whole chamber.

3. In an oil burning forge, a casing and a renewable lining composed of blocks of refractory material, the lower central block 95 at the back being wedge shaped in order to divide the flame vertically, and the remain- 100 ing back blocks being of standard rectangular construction and built to form concav- 105 ities at each side of the central wedge shaped block, thereby distributing the heat and causing the divided portions of the flame to ascend in spiral form for heating the articles to be forged.

4. In an oil burning forge, a casing and a 95 renewable lining composed of blocks of refractory material, the lower central block at the back being wedge shaped in order to divide the flame vertically, said central 100 block being thicker and higher than the lin- 105 ing blocks at each side in line therewith, and the remaining blocks above the central block being of a width substantially equal to that of the central block, thereby form- 110 ing concavities in the back wall for distrib- 115 uted the heat and causing the divided por- 120 tions of the flame to ascend in spiral form for heating the article to be forged.

In testimony whereof I have signed this specification.

CHARLES C. HANSEN.
